UNITED STATES PATENT OFFICE.

HOWARD S. GARDNER, OF EAST ORANGE, NEW JERSEY.

HOISTING APPARATUS.

1,365,979.

Specification of Letters Patent. Patented Jan. 18, 1921.

Application filed March 23, 1918. Serial No. 224,177.

To all whom it may concern:

Be it known that I, HOWARD S. GARDNER, a citizen of the United States, and resident of East Orange, county of Essex, State of New Jersey, have invented a certain new and useful Improvement in Hoisting Apparatus, of which the following is a specification.

My invention relates to apparatus for hoisting and discharging materials and has for its object to provide an improved and simplified construction in which the material is efficiently confined or carried during hoisting and in which it is efficiently discharged when desired. Other more specific objects of my improvement will appear from the description hereinafter and the features of novelty will be pointed out in the appended claims.

In the accompanying drawings, which illustrate an example of my invention, Figure 1 is a sectional elevation showing my improved apparatus in use in connection with building construction. Fig. 2 is an enlarged detail side elevation of the bucket forming part of my invention and illustrating parts of the guideway; Fig. 2^a is a detail view showing one of a pair of bucket supports; Fig. 3 is a front view of the bucket; Fig. 4 is a sectional elevation thereof on the line 4—4 of Fig. 3; Fig. 5 is an inverted plan view; Fig. 5^a is a detail section on the line 5^a—5^a of Fig. 5; Figs. 6 and 7 are views corresponding respectively to Figs. 2, 4 and 5 showing another form of my invention; Fig. 8 is a partial rear view thereof partly in section; Fig. 9 is a detail view of a pivot connection forming part of my invention; Fig. 10 is a detail view of a device for facilitating the filling or loading of the bucket; Fig. 11 is a detail elevation illustrating extensible links which may be included in the apparatus; Fig. 12 is a longitudinal section of one of said links; Fig. 13 is a detail side elevation showing one form of bucket supporting means forming part of my improvement and Fig. 14 is a detail front elevation thereof, partly in section.

My improved construction is particularly adapted for handling concrete and other coalescent material in building operations and construction work, and I have accordingly chosen an installation of this type as an example of my invention for the purposes of illustration and description.

As shown in the drawings, the apparatus comprises a pair of parallel guideways 15 which are arranged in the building or other structure in any suitable manner; these 60 guideways may be of any well known type adapted either to be built up in sections to keep pace with the construction work or to be installed in a structure after the latter has reached its intended height. When the 65 apparatus is used in construction work the guideways 15 preferably extend from a point below the lowermost part of the structure under construction, as, for instance, a pit 16 formed in the cellar of a building, 70 to the uppermost point at which material is to be delivered. The guideways 15 serve as guides for a bucket or receptacle 17 which is provided with rail-shoes 18 or their equivalents, arranged to coöperate with said guideways to maintain said bucket in its intended vertical or other path. The bucket 17 may be raised and lowered or otherwise manipulated in any suitable manner, as by means of a cable or the like 17^a having its one 80 end connected, for instance, at 19 with a frame 20 in which the bucket 17 is mounted and passing over a suitable pulley 21 to the drum of an engine or motor which provides the power whereby said bucket is operated. 85 The bucket 17 itself may be of any suitable dimensions and form and generally is provided with a bottom 22 inclining downwardly from the rear portion toward an exit opening 23 formed in the front wall 90 or portion of said bucket as shown in Fig. 4. The exit opening is normally closed by means of a gate, door or the like 24, carried by and depending, for instance, from hinges 25 journaled in suitable bearings 26 95 located at the proper points upon the bucket 17. In the preferred form the gate or door 24 is preferably provided with side wings 27 which in the closed position extend exteriorly along the side walls of the bucket 100 17 and in the open position of the gate bridge the spaces between it and the bucket and prevent spreading of the material during discharge.

As shown in Figs. 2 and 4 the gate 24 105 may be maintained in its closed position by means of a pair of bolts 28 having hooks 29 at their free ends and slidably mounted in bearings 30 secured to the bottom 22. The bolts 28 are spaced from each other in 110 the direction of the width of the bucket 17, and are pivotally connected at 31 with

cranks 32 mounted upon a shaft 33, which in turn is journaled in bearings 34 also fastened to the bottom 22. A crank 35 is carried by the shaft 33 at an intermediate point and is operatively connected, by means of a link or the like 36 with an arm 37 adjustably clamped upon a shaft 38, the latter passing through a hollow shaft referred to farther on as 57, said shaft 38 10 extending at one end beyond the bucket 17 and being journaled in bearings 39 also secured to the bottom 22. At its projecting end the shaft 38 carries an operating lever 40 which extends upwardly along and at a 15 distance from a side wall of the bucket and is preferably provided at its free end with a grip or handle 41, said lever 40, in the illustrated example, being movable in the arc of a circle between the members of a 20 segment 42 secured upon said bucket as shown in Fig. 2. In order that the lever 40 may be locked in position, in the predetermined adjustments, it may be provided with a spring latch 43 adapted to snap into 25 notches 44 and 45 formed in one or both members of the segment 42. When it is desired to release the lever 40 the latch 43 may be moved to an inoperative position, against the tension of its spring by means 30 of a finger piece 46 pivotally connected at 47 with the lever 40 and at 48 with the latch 43.

With this arrangement the hooks 29 of the bolts 28 project over the lower edge of the 35 gate 24 when the latter is in its closed position and thus lock said gate or door in this position; the bolts 28 are held against unintentional movement, owing to the fact that in the described position of the parts the 40 lever 40 inclines forwardly and the latch 43 is located in the notch 44 of the segment 42. The hooks 29 and bolts 28 may at all times be adjusted to properly lock the gate 24 in its closed position by rotatably adjusting 45 the arm 37 on the shaft 38, the arm as before stated being adjustably clamped thereon. When it is desired to release the gate the latch 43 is first removed from the notch 44 through the medium of the finger piece 46 50 after which the lever 40 is swung to the rear until the latch snaps into the notch 45. This causes the shaft 38 to be rocked and thereby causes the arm 37 to exert a pushing force upon the link or the like 36 which in turn 55 actuates the crank 35 and rocks the shaft 33. As the latter shaft is thus actuated it will operate the cranks 32, which in turn slidably move the bolts 28 in their bearings, in a direction to move the hooks 29 away 60 from the lower edge of the gate 24. The latter is thus released and under the force of the load or under the force of gravity or both swings to an open position. In the preferred form, a chain or chains 24^a are included for the purpose of limiting the out-

ward swinging movement of the gate. These chains have one end secured to the gate and their other end fastened to suitable U-bolts or the like carried by the bucket, one of said connections being preferably detachable to permit an unrestricted opening of the gate if this should be desired. To again lock the gate 24 after it has been swung to its closed position by gravity or otherwise, the latch 43 is released from the notch 44 and the lever 40 is swung to the front, until the latch 43 again snaps into the notch 44. This operation of the lever 40 brings about a reverse actuation of the parts and again brings the hooks 29 of the bolts 28 into operative engagement with the lower edge of the gate 24 which is thereby again firmly secured in its locked position.

With the arrangement so far described, the hooks 29 of the locking bolts 28 project into the path of the material or load as it is discharged from the bucket 17. In some cases, owing to the characteristics of the material being handled, it is desirable to avoid obstructions in the path of the material being discharged in order, for instance, to prevent injury to said material. For instance, the apparatus might be used for hoisting and discharging material contained in bags which might become torn during discharge by contact with said hooks.

In Figs. 6, 7 and 8 I have illustrated an example of my improvement in which no part of the gate locking mechanism projects into the path of the discharging material. In this form, bearings 34^a, corresponding to the bearings 34, are located near the lower edge of the bottom 22 and rotatably support a shaft 33^a corresponding to the shaft 33. At an intermediate point this shaft carries a crank 35^a, corresponding to the crank 35, and which is likewise operatively connected with the arm 37 of the shaft 38 by means of a link 36^a corresponding to the link 36. At or near its opposite ends the shaft 33^a carries arms 28^a which may be said to correspond in function at least, to the bolts 28 and which are provided at or near their free ends with studs or hooks 29^a which may be said to correspond to the hooks 29. In this form the side wings 27 of the gate 24 are continued downwardly in the form of depending lugs 27^a as shown in Figs. 6 and 7.

With the arrangement now being described and with the gate locked in its closed position, the arms 28^a project rearwardly from the shaft 33^a and the studs or hooks 29^a are in front of and in engagement with the lugs 27^a of the side wings 27, it being understood that in this position of the parts the lever 40 inclines forwardly and is locked in this position by the latch 43 which is located in the notch 44. The studs 29^a in co-operation with the lugs 27^a thus firmly and

securely hold the gate in its closed position. When it is desired to release the gate the latch 43 is withdrawn from the notch 44 and the lever 40 is swung to the rear until 5 said latch snaps into the notch 45. This actuation of the lever 40 rocks the shaft 38 and through the medium of the arm 37 exerts a pushing force upon the link 36^a which is communicated to the crank 35^a and causes 10 a rocking of the shaft 33^a whereby the arms 28^a are swung downwardly and the studs or hooks 29^a are thrown out of engagement with and below the lugs 27^a. The gate 24 in this manner is released and is now free to 15 swing to an open position as will be readily apparent. To again lock the door it is first returned to its closed position after which the latch 43 is withdrawn from the notch 45 and the lever 40 is swung toward the front 20 until the latch again snaps into the notch 44. This operation of the lever brings about a reverse actuation of the parts and again moves the studs or hooks 29^a in front of and in engagement with the lugs 27^a whereby 25 the gate is again firmly locked against movement. The proper operation between the studs 29^a and the lugs 27^a may, in this case, always be maintained by rotatably adjusting the arm 37 on the shaft 38 as hereinbefore described.

It will be seen, with the arrangement shown in Figs. 6, 7 and 8 that all parts of the gate locking and releasing mechanism are below and to the rear of the exit opening 23 of the bucket 17 and that no part of said mechanism at any time projects into the path of the material during discharge thereof. In this form the actual locking members, by being protected from contact 35 with the material being discharged, are always maintained in a condition of maximum efficiency. In other words, it is impossible for any material to collect upon said locking members to render the locking mechanism inoperative or at least ineffective, whereby the necessity for continual supervision in order to maintain the locking mechanism in an efficient condition is avoided.

50 My improvement further includes an improved chute whereby the space between the discharge end of the bucket and the receiving point or element for the material is bridged. The chute comprises a downwardly inclined bottom 49 and side walls 50 which extend upwardly at opposite sides of the bucket 17 and are pivotally and freely suspended thereon by means of rods or links 51 secured to said side walls 50 preferably by means of rivets and depending from pivotal connections 52 located at the upper portion of said bucket. In its normal, inoperative position, the chute is located beneath the bucket 17 and entirely inside of 55 the front portion thereof and thus does not

interfere in any way with the vertical movements of said bucket. The chute is capable of being swung, pendulum like on the pivots 52, to and from this inoperative position and in practice, when its use is required, is 70 swung forwardly relatively to said bucket to a position in advance of and in operative relation to the exit opening 23. In the illustrated example the mechanism for manipulating the chute and for locking it in either 75 its operative or its inoperative position comprises a pair of links 53 which are pivotally connected at 54 with the bottom 49 or with brackets carried thereby at points separated from each other as shown in Fig. 5. The 80 links 53 converge from the pivotal connections 54 toward their opposite ends which are pivotally connected at 55 with an arm 56 adjustably clamped upon and depending from a hollow shaft 57. The latter is rotatably mounted upon the shaft 38 and in a bearing 58 and extends beyond the bucket 17 at one side; at its projecting end the shaft 57 carries an operating lever 59, provided with a handle 59^a, and which also extends 85 upwardly along a side wall of said bucket and is movable between the two members of a segment 60 secured upon said bucket. The lever 59 also carries a spring latch 61 which co-operates with notches 62 and 63 formed 90 in one or both members of the segment 60, to lock the lever 59 in its adjusted positions; this latch 61 may also be operated by means of a finger piece 64 pivotally connected at 95 65 with the lever 59 and at 66 with the latch. 100

In its normal position the chute is located beneath the bucket, as before stated, the lever 59 being inclined forwardly and being locked in this position by the latch 61 which is located in the notch 62 and which thus 105 also locks the chute against any unintentional swinging movement relatively to the bucket. When it is desired to swing the chute to its operative position the latch 61 is first withdrawn from the notch 62 through 110 the medium of the finger piece 64, after which the lever 59 is swung toward the rear until said latch drops into the notch 63. The described movement of said lever 59 rocks the hollow shaft 57 about its axis and 115 swings the arm 56 forward whereby a pushing force is exerted upon the links 53, which force is communicated to the chute and swings it forwardly upon its pivots 52 in advance of the exit opening 23; the chute is locked in this position through the medium of the latch 61 and notch 63. To return the chute to its inoperative position the latch 61 is first withdrawn from the 120 notch 63 and the lever 59 swung back toward 125 the front whereby the parts are actuated in a reverse direction and said chute is swung back beneath the bucket. By connecting the links 53 with the chute at its bottom and by locating and correlating the co-operating 130

parts in approximately the relation shown in the illustrated example, the chute is firmly braced when in its operative position against shocks produced by the material during discharge thereof; the chute manipulating mechanism with this arrangement also neutralizes such shocks and thus reduces the danger of injury to a minimum. It will be understood that, in practice, the chute is always manipulated before the gate locking mechanism is actuated; that is the chute is first swung to its operative position before the locking mechanism is operated to release the gate and similarly the chute is always returned to its inoperative position before the locking mechanism is operated to lock the gate.

The range of movement of the chute may be changed and adjusted to meet all conditions, by rotatably adjusting the arm 56 on the shaft 57, the arm being adjustably clamped upon said shaft for this purpose.

Hereinbefore in the description I have spoken of the necessity for returning the gate 24 to its closed position before the locking mechanism is actuated to lock said gate against opening. In the preferred form of my improvement this return of the gate to its closed position may be automatically accomplished for instance, as shown in the illustrated examples. A member 67 is pivotally connected at 68 with one of the chute suspending links 51 and at 69 with an intermediate point of another member 70, the latter having its one end pivotally connected at 71 with a bracket 72 secured upon the bucket 17. In the preferred arrangement the pivots 68, 69 and 71, which usually comprise bolts, each extend through a tubular washer or sleeve 73 which is slightly longer than the thickness of one of the members which are pivotally connected and which sleeve is located in a suitable aperture in said one member between the nut whereby said bolt is secured in place and the other member of the pivotal connection as shown in Fig. 9. With this arrangement it is impossible to bind together any of the members which are pivotally connected owing to the presence of the washers 73 so that the relative movement of said members is always brought about with a minimum of effort. The free end portion of the member 70 is arranged to coöperate with a pin or stud 74 located upon a side wing 27 of the gate 24.

As the chute is swung forward to its operative position as hereinbefore described, the members 67 and 70 will be pivotally actuated and straightened out and the free end portion of the member 70 will be swung away from the pin or stud 74. This leaves the gate 24 free to swing to its open position, after the locking mechanism is operated or released, as hereinbefore described. The

parts are so proportioned and located with respect to each other that the outward movement of the stud 74 in the normal opening movement of the gate does not carry said stud materially beyond the point where the arc described by said stud 74 during said opening movement intersects the arc described by the free end of the member 70 during the same movement. In other words, the member 70 swings in an arc having the pivot 71 as a center, while the stud 74 swings in a relatively larger arc having the pivot 25 as a center; this permits the stud 74 and member 70 to swing clear of each other and allows the gate 24 to open to an abnormal extent if this should become necessary because of the character of the material being handled. When the chute is returned to its inoperative position, the members 67 and 70 will be folded as it were and the free end portion of the member 70 will finally engage the stud 74; as the return movement of the chute is continued said member 70 will press rearwardly upon said stud 74 and will thus swing the gate 24 to its fully closed position after which the locking mechanism may be actuated as previously set forth. It will be understood that the members 67 and 70 and coöperating stud 74 may be duplicated on both sides of the bucket if this should be desired. The arrangement described insures the proper final engagement of the elements 27^a and 29^a in constructions in which the gate 24 swings toward its closed position by gravity but does not swing far enough in this direction to bring the elements 27^a and 29^a into proper coöperative relation to each other. When the elements 27^a and 29^a are in operative engagement with each other and the gate 24 is fully locked, the member 70 will be slightly spaced from the stud 74, say a quarter of an inch or so. No part of the pressure or other strains exerted by the load upon said gate 24 is therefore communicated to the chute which is thus protected against injury from these causes.

When the bucket is in its lowermost position ready to be loaded the bottom thereof rests upon supports 75 located at the lower ends of the guides 15 and each composed, for instance, of a number of sections joined together and having their upper surfaces inclined at angles corresponding to each other and to the angle of the bottom 22. In addition the bucket is preferably provided with a pair of shoes 76 depending from the bottom 22 and having their free ends curved as at 77. These shoes 76 are arranged to pass behind the supports and engage the one vertical surface of each support 75 and thus serve to hold the bucket rigidly in position during loading thereof. In other words these shoes, in coöperation with the supports, brace the bucket firmly against any strains

in a direction toward the front of said bucket, during loading. In constructions in which the bottom of the bucket is inclined downwardly toward the front this is important, as the tendency of the load to slide down upon said inclined bottom results in considerable strain toward the front of the bucket. With my improved arrangement such strains are neutralized by the shoes and supports and are not transmitted, to any appreciable extent, to the guideways, which are thus protected from distortion during loading of the bucket.

My improvement further includes an auxiliary chute which is arranged to bridge the space between the bucket 17 and a storage hopper, a concrete mixer or any other source from which the material is loaded into said bucket. In the illustrated example, as disclosed in Figs. 1 and 10 I have shown the auxiliary chute in combination with a storage hopper in which concrete from a concrete mixer is stored.

As shown, the auxiliary chute comprises a platform 77 having upright sides 78 provided at their front edges with projections 79 for instance, in the form of short angle irons. The platform 77 is carried by members 80 secured to angle irons 81 pivoted at 82 upon the support 83 for the storage hopper 84 which is provided with a sliding door 85 and receives its contents for instance, from a concrete mixer 86. The angle irons 81 extend in one direction into the path of the bucket 17 as at 81^a and in the other direction beyond the members 80 and carry counter balance weights 87. The parts are so arranged and proportioned with respect to each other that the auxiliary chute will bridge the space between the hopper 84 and the bucket 17 when the latter is in position for loading.

In practice, as the bucket 17 descends it will finally engage the projecting ends of the beams 81 at 81^a and thus swing the platform 77 and sides 78 against the force exerted by the weights 87, to the operative position shown in Fig. 1; in this position the material will pass from the hopper 84, as soon as the door 85 is opened, to the platform 77 and to the bucket 17, the sides 78 preventing said material from spreading laterally on said platform. After the bucket 17 has received the desired quantity of material the door 85 is closed and the bucket is raised to the point at which delivery of said material is to take place. As soon as the bucket 17 begins to rise the weights 87 will swing the beams 81, members 80, platform 77 and sides 78 to an inoperative position in which no part of the auxiliary chute interferes with the vertical movement of said bucket. The movement of the platform 77 and its connected parts to the inoperative position is arrested as soon

as the projections 79 contact with the hopper 84 or some portion of its support. It will be understood that the parts are arranged so that this result will be obtained; in this manner the tilting of auxiliary chute to a 70 position in which it could be entirely out of coöperative relation with the bucket is prevented.

In operation the bucket, after being loaded, is raised through the medium of suitable machinery to the level at which the material is to be delivered. When this level has been reached the level 59 is swung toward the rear, thus swinging the chute from its inoperative position to an operative position as hereinbefore described. After this has been done the lever 40 is actuated to release the gate 24 also in the manner previously set forth and permit it to swing to an open position. After the material has been discharged the chute is first returned to its inoperative position after which the gate-locking mechanism is actuated to again lock the gate in its closed position. The bucket is then lowered and refilled after 90 which the operations above described are repeated.

Instead of clamping the arms 37 and 56 upon the respective shafts 38 and 57 to permit the gate locking devices and the range 95 of movement of the chute to be adjusted as hereinbefore described, said arms 37 and 56 may be keyed or otherwise fixed upon said shafts. In this case the links 36, 36^a and 53, 53^a may be made adjustable as to length for the same purposes and as shown in Figs. 11 and 12 may comprise sections 36^b and 36^c and 53^b and 53^c respectively, adjustably connected together by means of bolts *a* and slots *b* for instance as illustrated. 105

Instead of constructing the shoes 76 and supports 75 as shown for instance in Fig. 2, these elements may be constructed as illustrated in Figs. 13 and 14. In this case the shoes 76^a are straight horizontal members 110 carried by the bucket 17 and secured in position in any suitable manner as by being riveted to the lower ends of channel irons 20 located at the opposite sides of the bucket 17 and projecting below the same; suitable plates and angle irons may be provided to increase the rigidity of the construction to a maximum extent. When the bucket is in its lowest position these shoes 76^a rest upon the upper horizontal surfaces of supports 115 120 75^a corresponding in function and location to the supports 75.

When constructed as in Fig. 2 the shoes 76, when in engagement with the supports 75 are sometimes forced into such close contact therewith under the pressure exerted by the load in the bucket as to interpose a resistance to the raising of the latter, this being due to the inclinations of the bottom of the bucket and the upper surfaces of the sup- 130

ports 75. With the form of construction shown in Figs. 13 and 14 even the slight disadvantage recited above is overcome.

My invention is extremely simple in construction and efficient in operation and requires no skilled attention, either in operation or in installation. The apparatus may be used for handling any kind of material either loose or in bags or other containers.

10 In my improved apparatus the parts are all constructed and combined in such a manner that the effects of all strains, stresses and shocks are neutralized, thus prolonging the life of the apparatus and rendering it proof 15 against rough and unusual usage.

Various changes in the specific forms shown and described may be made within the scope of the claims without departing from the spirit of my invention.

20 I claim:—

1. In a hoisting apparatus, a bucket having an exit opening, a movable door for said opening, a chute normally located beneath said bucket, means pivotally connected with said bucket for freely suspending the chute therefrom, and means connected directly with said chute whereby it is swung on its pivotal connections laterally of said bucket to an operative position in advance of said 30 exit opening and back again.

2. In a hoisting apparatus, a bucket having an exit opening, a movable door for said opening, a chute normally located beneath said bucket, means pivotally connected with said bucket for freely suspending the chute therefrom, and means connected directly with said chute at the rear edge of its bottom whereby said chute is swung on its pivotal connections laterally of said bucket 35 to an operative position in advance of said exit opening and back again.

3. In a hoisting apparatus, a bucket having an exit opening, a movable door for said opening, a chute normally located beneath said bucket, means pivotally connected with said bucket for freely suspending the chute therefrom, a link pivotally connected directly to said chute and a lever pivotally mounted on said bucket and pivotally connected with said link whereby said chute is 40 swung on its pivotal connections laterally of said bucket to an operative position in advance of said exit opening and back again.

4. In a hoisting apparatus, a bucket having an exit opening, a movable door for said opening, means for locking said door in its closed position and for releasing same, a chute movably mounted on said bucket, means for moving said chute to and from 45 an operative position and means other than the chute itself whereby said door is closed as said chute is moved to its inoperative position.

5. In a hoisting apparatus, a bucket having an exit opening, a movable door for said 50

opening, a chute normally located beneath said bucket, means pivotally connected with said bucket for freely suspending the chute therefrom, means for swinging said chute to and from an operative position, means operatively connected with said chute suspending means whereby said door is closed as said chute is swung to its inoperative position and means for locking said door in its closed position and for releasing same. 75

6. In a hoisting apparatus, a bucket having an exit opening, a swinging door for said opening and having side wings, a chute pivotally suspended on said bucket, means for swinging said chute to and from an operative position, a projection on one of the wings of said door, a link pivotally connected with the bucket and arranged to engage said projection, a second link pivotally connected with one of said bucket carrying members and with said first link whereby the latter is engaged with said projection to close said door as the bucket is swung to an inoperative position and means for locking said door in its closed position and for 80 releasing same.

7. In a hoisting apparatus, a bucket having an exit opening, a pivotally suspended door for said opening having rearwardly extending side wings, a lug on one of said wings, a shaft journaled on the bottom of said bucket rearwardly of said exit opening, a locking member operatively connected with said shaft and arranged to engage said lug rearwardly of said exit opening for locking said door in its closed position, a link operatively connected with said shaft and a lever pivotally mounted upon said bucket and pivotally connected with said link whereby said locking member is moved to 95 100 and from an operative position.

8. In a hoisting apparatus, a bucket having an exit opening, a pivotally suspended door for said opening having rearwardly extending side members, lugs depending 110 from said side members, a shaft journaled on the bottom of said bucket rearwardly of said exit opening, a pair of locking members operatively connected with said shaft and arranged to engage said lugs rearwardly of 115 said exit opening to lock the door in its closed position, a crank carried by said shaft, a second shaft journaled on the bottom of said bucket, an arm carried by said second shaft, a link operatively connected 120 with said crank and with said arm and a lever carried by said second shaft whereby said locking members are moved to and from an operative position.

9. In a hoisting apparatus, a bucket having an exit opening, a pivotally suspended door for said opening provided with side wings, a projection on one of said side wings, a shaft journaled on the bottom of said bucket and rearwardly of the exit open- 125 130

ing, a member carried by said shaft, a stud on said member arranged to engage said wing projection rearwardly of said exit opening to lock the door in its closed position and means for actuating said shaft to move said member and stud to and from an operative position.

10. In a hoisting apparatus, a bucket having an exit opening, a pivotally suspended door for said opening provided with side wings, projections depending from said side wings, a shaft journaled on the bottom of said bucket and rearwardly of said exit opening, a pair of members carried by said shaft, a stud on each member arranged to engage said wing projections rearwardly of said exit opening to lock said door in its closed position, a crank carried by said shaft, a second shaft journaled on the bot-

tom of said bucket, an arm carried by said second shaft, a link connected with said arm and with said crank and a lever carried by said second shaft whereby said members and studs are moved to and from an operative position.

11. In a hoisting apparatus, a pair of upright guideways, a bucket arranged to travel lengthwise thereof, a stationary, rigid support at the lower end of each guideway and having a horizontal upper surface and shoes carried by said bucket and having horizontal members arranged to rest upon the horizontal surfaces of said supports whereby said bucket is supported in its lowermost position during loading thereof.

In testimony whereof I have hereunto set my hand.

HOWARD S. GARDNER.
